UNITED STATES PATENT OFFICE

2,529,161

REGISTER CONTROL SYSTEM

Leroy U. C. Kelling and Lowell H. Sheets, Schenectady, N. Y., assignors to General Electric Company, a corporation of New York

Application April 30, 1948, Serial No. 24,154

3 Claims. (Cl. 250—27)

1

This invention relates to control systems, more particularly to register control systems for controlling the positional relationships of a length of material provided with spaced reference marks and an element operating thereon such as a rotating knife for severing the length of material in register with the marks, and it has for an object the provision of an improved control system of this character.

More particularly the invention relates to register control systems in which the length of material travels at relatively slow or medium speeds and in which but a medium degree of accuracy in the positional relationship of the reference indicia and the operating element is not required. For example, in machines for wrapping articles such as candy and gum with a label or design appearing on each wrapper, a strip having labels or designs printed on it in succession is fed into the cutting and wrapping machine. In such a machine an accuracy of register between the knife and the design is required which will insure that the strip is cut between the labels or designs. Usually the required accuracy of cutting varies between one-sixty-fourth inch and one-sixteenth inch. In this relatively low speed field the number of machines is relatively large and consequently low cost of the control is important. Accordingly a further object of the invention is the provision of a register control system which is simple, reliable and inexpensive.

In carrying the invention into effect in one form thereof, a photoelectric scanning head responds to reference marks on the moving length of material to provide a voltage impulse for each mark. A selector switching means driven by the element which operates on the material produces voltage impulses which are in timed relationship to the operation of the element. The impulses from the scanning head are supplied to the anode of a mixing electric valve and the impulses from the selector switch are supplied to the grid. If an error exists, i. e., if the element is not in correct register with the reference marks on the strip, voltage impulses are received simultaneously on the grid and anode of the mixing valve. This causes a triggering circuit to initiate conduction in a thyratron. A timing circuit maintains the triggering circuit energized for a predetermined interval of time and the triggering circuit in turn maintains the thyratron conducting for the same fixed interval. An electric motor which is energized in response to conduction by the thyratron operates through a differential device to introduce a correction in the relative positions of the element and the length of material.

In illustrating the invention in one form thereof, it is shown as embodied in a cut-off register control system, i. e., a system for controlling a cutter to cut sheets from a moving length of

material with the cut edges in correct register with designs previously printed on the material.

For a better and more complete understanding of the invention reference should now be had to the following specification and to the accompanying drawing of which the single figure is a simple schematic diagram of an embodiment of the invention.

Referring now to the drawing, a length of material 1, such as a web of paper having a succession of designs printed thereon, is drawn from a roll 2 by means of draw rolls 3 and travels in the direction of the arrow to a cutter 4.

The draw rolls and the cutter are driven by suitable driving means illustrated as an electric motor 5. The drive shaft of the motor is directly connected to the cutter 4 and through bevel gearing 6 and a mechanical differential device 7 to the draw rolls 3. The differential device comprises an input gear 7a, an output gear 7b and a ring gear 7c which is driven by an electric motor 8. The motor 8 is referred to as the correction motor.

Preferably the ratio of the gearing 6 is such that when the correction motor is at rest, the peripheral speed of the draw rolls exceeds the peripheral speed of the cutter rolls by a small amount, e. g. between .5 per cent and 2 per cent. Thus the material is overfed to the cutter so that an error in register between the cutter and the printed designs on the length of material is constantly accumulating.

As shown, the correction motor 8 is a direct current motor. Power is supplied to its armature from a suitable source of alternating voltage such as the supply conductors 9 and 10 to which the armature is connected through a suitable electric valve such as the thyratron 11. The thyratron is provided with an anode 11a, a cathode 11b, and a control grid 11c. An alternating hold-off voltage is supplied to the grid and cathode of the thyratron from the secondary winding 12a of a transformer 12 of which the primary winding 12b is connected to a suitable source which may be and preferably is the supply conductors 9, 10 from which the thyratron and correcting motor are supplied. The polarity of the connections to the secondary winding are such that the voltage supplied to the grid of the thyratron is 180° out of phase with the anode voltage so that the thyratron is normally non-conducting and the correcting motor is at standstill.

For the purpose of comparing the register, i. e., the relative positions of the cutter and the designs, the length of material is provided with a succession of reference indicia or register marks 13 in predetermined relationship with the printed designs. Preferably these marks are printed on the material simultaneously with the printing of the designs.

The cutter is provided with means for provid-

ing an indication of its position. These means are referred to as a selector switch. This selector switch may take the form of a mechanical switching device or it may take form of the photoelectric device which is illustrated in the drawing. It comprises a disk 14 mounted on the cutter shaft and a photoelectric scanning head 15. Preferably the disk has a dark background upon which is marked a white segment 14a. The segment may embrace from 10° to 120° of the disk.

The register marks 13 pass beneath a photoelectric scanning head 16 which comprises a lamp 17 and a photoelectric cell 18 which is focused on the path of the register marks through a suitable optical system. The photoelectric cell 18 is connected across a suitable source of direct voltage which is illustrated as a single phase diacritic rectifier 19 supplied from a suitable source of alternating voltage which may be and preferably is the source 9, 10. A voltage divider comprising a plurality of resistors 20, 21, 22, 23, 24 and 25 is connected across the output terminals of the rectifier. The junction point of resistors 23 and 24 is grounded. The photoelectric cell 18 is connected in a circuit which extends from the point 20a on the divider through the photoelectric cell 18 and resistor 26 to ground. A switch 27 is provided for changing the connection so that the circuit extends from the point 20a on the divider through resistor 28 and the photoelectric cell to ground. The position of the switch 27 determines whether the system operates upon an increase or a decrease of light. When the switch is in the position in which it is illustrated the system operates upon a decrease in light.

The photoelectric cell circuit is coupled to the grid of an amplifier valve 29 through a capacitor 30, resistor 31 and potentiometer 32. The valve 29 is provided with an anode 29a, a cathode 29b and a control grid 29c which is directly connected to the slider 32a of the potentiometer. A voltage dropping resistor 33 is connected between the anode 29a and the positive terminal 19a of the rectifier. The cathode 29b is directly connected to the point 22a on the voltage divider.

As shown, the scanning head of the photoelectric selector switch device 15 comprises a lamp 34 and a photoelectric cell 35. A beam of light from the lamp 34 passes through focusing lenses to illuminate the path of the segment 14a, and light is reflected from the segment to the photoelectric cell 35 which is focused upon the segment by means of focusing lenses. The photoelectric cell 35 is connected in series with resistor 36 between the point 21a on the divider and the negative terminal 19b of the rectifier.

For the purpose of comparing the times of occurrence of signal voltage pulses from the photoelectric cells 18 and 35, an electronic mixer is provided. It comprises the left-hand conducting path of a twin triode electric valve 37. This left-hand path includes an anode 37a, a cathode 37b and a control grid 37c. A capacitor 38 couples the anode 37a to the anode of the amplifier valve 29, and the grid 37c is directly connected through a resistor 38b to the junction point of the resistor 36 and photoelectric cell 35.

An electronic triggering circuit is controlled by the mixer valve to initiate and maintain conduction in the thyratron 11 for a predetermined interval of time. It comprises a twin triode electric valve 39, the right-hand conducting path of the valve 37, and a timing circuit which includes the capacitor 40. The right-hand path of valve 37 includes an anode 37d, a cathode 37e

and a control grid 37f. The anode 37d is connected through two voltage dropping resistors 41 and 42 to the positive terminal 19a of the rectifier and the cathode 37e is connected to the negative terminal 19b.

The left-hand conducting path of valve 39 contains an anode 39a, a cathode 39b, and a control grid 39c. Similarly the right-hand conducting path includes an anode 39d, a cathode 39e and a control grid 39f.

A voltage dropping resistor 43 is connected between the anode 39a and the junction point 41a of resistors 41 and 42, while the cathode 39b is connected through a resistor 44 to the point 24a on the voltage divider. Between the anode 37d and the negative terminal 19b of the rectifier two resistors 45 and 46 are connected in series, and to their common point 45a are connected the cathode 37b of the mixing valve and the grid 39c of the triggering circuit valve 39.

The timing circuit extends from the positive terminal 19a of the rectifier through resistor 41, resistor 43, capacitor 40, adjustable potentiometer 47 and resistor 48 to the negative terminal 19b of the rectifier. In this connection one terminal of the timing circuit capacitor 40 is connected to the point 43a which is connected to the anode 39a of valve 39, and the other terminal is connected to the grid 37f of valve 37.

Alternating voltage is supplied to the right-hand conducting path of valve 39 from the secondary winding 12c of transformer 12. The cathode 39e is connected to one terminal of the secondary winding and the anode 39d is connected through the primary winding 49a of a transformer 49 to the other terminal of the secondary winding 12c. The grid 39f of the right-hand path of valve 39 is connected to the cathode 39b of the left-hand path. The secondary winding 49b of transformer 49 is connected in the grid to cathode circuit of the thyratron 11.

Initially the relative positions of the scanning heads 15 and 16 with respect to the segment 14a on the disk and the reference marks on the strip are adjusted so that the voltage pulses produced by the scanning heads do not overlap, i. e., do not occur simultaneously when the cutter 4 is in proper register with the register marks 13.

The voltages applied to the grid 39c and cathode 39b of the triggering valve are selected so that the valve is normally non-conducting. On the other hand, the voltages applied to the cathode 37e and the grid 37f of the timing circuit valve are such that it is normally fully conducting.

With the foregoing understanding of the elements, the operation of the system will readily be understood from the following description.

As each reference mark on the strip passes beneath the scanning head 16, the light reflected to the photoelectric cell 18 is decreased thereby decreasing the current through the cell and correspondingly decreasing the voltage drop across the resistor 26 for the period that the reference mark is beneath the photoelectric cell. The resulting negative voltage pulse at the point 18a is indicated graphically in the circle 50. It is transmitted through the coupling condenser 30 and applied as a negative voltage pulse to the control grid 29c of the amplifier valve. The signal is amplified and appears as a large positive pulse at the anode terminal 33a of resistor 33. It is illustrated by the positive voltage pulse in the circle 51. The amplified voltage pulse is transmitted through the coupling capacitor 38 and appears as a positive pulse on the anode 37a

of the mixing valve 37 as indicated by the pulse within the circle 52.

Once during each revolution of the disk 14, the white segment 14a passes beneath the scanning head and increases the light reflected by the disk to the photoelectric cell 35. This increases the current in the photoelectric cell circuit and correspondingly increases the voltage drop across the resistor 36 so that a positive voltage pulse appears at the point 35a, as represented graphically by the positive pulse within the circle 53. It is applied as a positive pulse (shown within the circle 54) to the control grid 37c of the mixing valve. Owing to the length of the white segment 14a in comparison with the length of a register mark, the pulse applied to the grid 37c is of greater duration than the pulse applied to the anode as indicated by a comparison of the width of the pulses within the circles 54 and 52.

When the cutter is in proper register with the register marks on the length of material, the pulses applied to the anode 37a and to the grid 37c do not overlap and consequently the left-hand path of valve 37 remains non-conducting. No signal is transmitted to the grid 39c of the triggering circuit valve 39. Consequently the thyratron 11 remains biased to cut-off and the correction motor 8 remains at standstill.

However, since the feed rolls feed a little more than one sheet length of material per machine cycle, i. e., per rotation of the cutting rolls, a condition of misregister soon develops. When a predetermined amount of error, i. e., misregister between the register marks and the cutter, has accumulated, the voltage pulses supplied from the photoelectric cell 18 to the anode 37a and from the photoelectric cell 35 to the grid 37c overlap, i. e., occur simultaneously. This overlap of the voltage pulses on the anode and grid is illustrated graphically within the circle 55.

During the interval that both pulses overlap, the anode 37a and grid 37c are simultaneously positive and current flows in the anode-cathode circuit, thereby increasing the voltage drop across the resistor 46. This results in the voltage at the grid 39c becoming sufficiently positive to render the left-hand path of the triggering circuit valve conducting, which in turn produces a large voltage drop across resistor 43, thereby suddenly making the point 43a more negative by the amount of this voltage drop. Since the condenser 40 cannot discharge instantaneously, the voltage of its terminal 40a suddenly becomes more negative by the amount of the voltage drop across resistor 43. Consequently, the voltage at the grid 37f which is connected to point 40a becomes so negative that the right-hand path becomes non-conducting. When the valve ceases conduction the voltage drop across resistor 42 decreases and the voltage at the point 42a becomes increasingly positive. This results in maintaining the voltage of the grid 39c sufficiently positive to maintain conduction in the left-path of valve 39 after the left-hand path of valve 37 has become nonconducting following the termination of the voltage pulse supplied to its anode.

At the end of a predetermined interval of time from the beginning of conduction in the left-hand path of valve 39, the condenser 40 has discharged sufficiently to permit the voltage of grid 37f to rise to the value at which the right-hand path of valve 37 again becomes conducting. The restoration of conduction in the right-hand path of valve 37 increases the voltage drop across resistor 42 thereby causing the voltage at the grid

39c to become sufficiently negative to stop conduction in the left-hand path of valve 39.

The predetermined interval of time during which the left-hand path of valve 39 remains conducting after conduction begins depends upon the rate of discharge of the capacitor 40 which in turn depends upon the adjustment of the potentiometer 47 in the discharge circuit. The voltages at the anode 37d, the grid 37f, the grid 39c and the anode 39a during this predetermined interval of time are illustrated graphically within the circles 56, 57, 58, and 59 respectively.

During the predetermined interval in which the left-hand path of valve 39 is conducting, the voltage drop across the resistor 44 is increased and the voltage at the point 44a and at the grid 39f become sufficiently positive to initiate conduction in the right-hand path of the valve 39. The voltage at the point 44a and at the grid 39f during this interval of time are shown graphically within the circle 60. The alternating voltage which is supplied to the anode 39d and cathode 39e is rectified by the valve action and the rectified voltage which appears at the anode 39d is illustrated within the circle 61. Since this rectified voltage contains a periodically varying component, a periodically varying voltage is induced in the secondary winding 49b which is in phase with the line voltage and therefore 180° out of phase with the hold-off voltage which is supplied to the grid 41c of the thyratron from the secondary winding 42a. The alternating hold-off voltage is illustrated within the circle 62 and the periodically varying voltage induced in the secondary winding 49b is illustrated within the circle 63. Since these two voltages are 180° out of phase, the voltage induced in the secondary winding 49b overcomes the bias of the hold-off voltage and the thyratron 11 becomes conducting and supplies a rectified voltage to the correction motor 8 for the predetermined interval of time the triggering circuit is active.

In response to energization, the correction motor rotates in a direction such that the revolutions of the output element 7b of the differential device 7 are the difference between the revolutions of the input element 7a and the input element 7c. In other words, the speed of the draw rolls is retarded with respect to the speed of the cutting cylinders so that correct register between the register marks and the blades of the cutter is restored. At the end of the predetermined interval of time the thyratron becomes nonconducting and the correction motor is stopped.

Owing to the overfeed of the strip with respect to the cutter, the register marks again become out of register with the cutter and the operation described in the foregoing is repeated.

The predetermined interval of time during which the correction motor is energized in response to an out-of-register condition may be varied by varying the position of the slider 47a of the rheostat 47. The discharge circuit for the capacitor 40 extends from the lower terminal of the capacitor 40, rheostat 47 and resistor 48, to the negative terminal of the rectifier and from the positive terminal of the rectifier through resistors 41 and 43 to the positive terminal of the capacitor. In one embodiment of the invention the resistor 41 is 39,000 ohms; resistor 43, 100,000 ohms; rheostat 47, 3,000,000 ohms, and resistor 48, 100,000 ohms.

After the capacitor has discharged and the right-hand path of the valve 37 has again be-

come conducting, the capacitor is recharged by grid rectification. The circuit is from the positive terminal of the rectifier through resistors 41 and 43, capacitor 40, grid 37f, cathode 37e, to the negative terminals of the rectifier. Thus the greater portion of the high resistance of the discharge circuit is by-passed and the capacitor is recharged in a much shorter time than was required for the discharge. Thus the system is quickly reset and placed in condition for a subsequent operation, as described in the foregoing. If desired, the control may be arranged for operation with underfeed of the material by selecting a proper ratio of the gearing 6 and by reversing either the field or armature connections to the correction motor 8.

Although in accordance with the provisions of the patent statutes this invention is described as embodied in concrete form and the principle thereof has been explained together with the best mode in which it is now contemplated applying that principle, it will be understood that the elements shown and described are merely illustrative and that the invention is not limited thereto since alterations and modifications will readily suggest themselves to persons skilled in the art without departing from the true spirit of this invention or from the scope of the annexed claims.

What we claim as new and desire to secure by Letters Patent of the United States is:

1. A control system comprising a source of direct voltage, a first electric valve having an anode, a cathode and a control grid and having its anode-cathode circuit connected to be supplied from said source, means for producing a voltage pulse, means for producing another voltage pulse, means responsive to the overlapping in time of said pulses for producing a control voltage pulse, a direct conductor connection from said control voltage pulse producing means to said grid for supplying said control voltage pulse to said grid to initiate conduction of said valve, and means for maintaining said valve conducting for a predetermined fixed interval of time comprising a normally conducting second electric valve provided with an anode, a cathode and a control grid and having its anode-cathode circuit connected to be supplied from said source, a connection including a capacitor from the anode of said first valve to the grid of said second valve for rendering said second valve nonconducting in response to initiation of conduction in said first valve, a timing circuit including said capacitor for maintaining said second valve nonconducting for said predetermined interval of time, and a connection from the anode of said second valve to the grid of said first valve for maintaining said first valve conducting for said interval of time and for rendering said first valve nonconducting at the end of said interval.

2. A control system comprising a source of direct voltage, a first electric valve having an anode, a cathode and a control grid and having its anode-cathode circuit connected to be supplied from said source, means for producing a train of periodic voltage pulses, means for producing a second train of periodic voltage pulses, means responsive to the overlapping in time of a pulse of said first train and a pulse of said second train for producing a control voltage pulse, a direct conductor connection from said control voltage pulse producing means to said grid for supplying said control voltage pulse to said grid to initiate conduction of said valve, and means for maintaining said valve conducting for said predetermined interval of time after initiation of conduction therein and for rendering said first valve nonconducting at the end of said interval.

voltage pulse producing means to said grid for supplying said control voltage pulse to said grid to initiate conduction of said valve, and means for maintaining said valve conducting comprising a normally conducting second electric valve having an anode, a cathode and a control grid and having its anode circuit connected to be supplied from said source, a connection including a capacitor from the anode of said first valve to the grid of said second valve for rendering said second valve nonconducting in response to initiation of conduction in said first valve, a timing circuit including said capacitor for maintaining said second valve nonconducting for said predetermined interval of time and a connection from the anode of said second valve to the grid of said first valve for supplying a positive bias voltage to the grid of said first valve to maintain said first valve conducting for said interval of time and to render it nonconducting at the end of said interval.

3. A control system comprising a source of direct voltage, a first electric valve having an anode, a cathode and a control grid and having its anode-cathode circuit connected to be supplied from said source, a first means for producing a train of periodic voltage pulses, a second means for producing a second train of periodic voltage pulses, means responsive to the overlapping in time of a pulse of said first train and a pulse of said second train for supplying a control voltage pulse to said grid to initiate conduction of said valve comprising a normally nonconducting electric valve having a cathode connected to said grid and to the negative side of said source, an anode connected to said first pulse producing means and a control grid connected to said second pulse producing means, and means for maintaining said first valve conducting for a predetermined interval of time comprising a normally conducting third electric valve having an anode, a cathode and a control grid and having its anode-cathode circuit connected to be supplied from said source, a connection including a capacitor from the anode of said first valve to the grid of said third valve for rendering said third valve nonconducting in response to initiation of conduction in said first valve, a timing circuit including said capacitor for maintaining said third valve nonconducting for said predetermined interval of time, an adjustable resistor in said timing circuit for adjusting said interval of time to a desired value, a connection from the anode of said third valve to the grid of said first valve for maintaining said first valve conducting for said predetermined interval of time after initiation of conduction therein and for rendering said first valve nonconducting at the end of said interval.
